BARREL

Simon Deutsch, Milwaukee, Wis., assignor of fifty-one per cent to Hugo Weiner, twenty-one and one-half per cent to Alfred E. Fein, and six per cent to Fannie Sax, all of Milwaukee, Wis.

Application August 20, 1934, Serial No. 740,691

2 Claims. (Cl. 220—10)

This invention appertains to shipping and storage vessels, and more particularly to metallic barrels for the reception of liquids, such as beer.

It has heretofore been proposed to utilize metallic beer barrels. However, these barrels are open to serious objection, in that they are difficult to pitch, and the same transmit temperature changes quickly to their contents, which is particularly detrimental to the best keeping of beer. Also, due to the rough handling of the barrels, the same very often spring a leak. Not only are the leaks difficult to locate, but in some instances are practically impossible to repair. This results in the necessity of junking the entire barrel.

Therefore, one of the salient objects of my invention is to provide a metallic barrel, which will effectively overcome the above mentioned difficulties and which is so constructed that the temperature of the barrel contents can be kept at its original temperature a relatively long time.

Another important object of my invention is to provide a barrel having an inner liner and an outer protecting casing, the liner being held in spaced relation to the casing by non-heat conducting and cushion strips, so that temperature changes will not be readily transmitted to the liner, and whereby the liner will be protected from shocks.

Another object of my invention is to provide a barrel having a removable inner liner for receiving the beer, the liner being of such a character as to permit the pasteurization of beer directly therein, which has heretofore been impossible with ordinary metallic barrels.

A further object of my invention is to provide a barrel embodying a protecting casing and an inner liner formed from non-corrosive material, such as aluminum or copper, whereby the necessity of pitching the barrel is eliminated.

A further object of my invention is to provide novel means for constructing the casing, whereby the same can be readily taken apart and assembled, so as to facilitate the initial building of the barrel and to permit the convenient replacing of the liner, should the same spring a leak, the liner being of relatively inexpensive nature, so as to allow the casting of the same aside (should the same be beyond repair) for a new liner, whereby the junking of the entire barrel is eliminated.

A further object of my invention is to provide a barrel embodying a sectional casing and an inner liner, with novel means for detachably connecting the sections together, whereby movement of the liner in the casing will be prevented, the

casing carrying the spacing strips for the liner in a novel manner to prevent displacement thereof.

A still further object of my invention is to provide a metallic barrel of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings:

Figure 1 is a side elevation of one form of my improved barrel, with parts thereof broken away and in section to illustrate structural details.

Figure 2 is a horizontal section taken through my improved barrel on the line 2—2 of Figure 1.

Figure 3 is an enlarged fragmentary, detail vertical section illustrating my novel bung.

Figure 4 is a central vertical section through another form of my novel barrel, the section being taken on the line 4—4 of Figure 5.

Figure 5 is a horizontal section taken on the line 5—5 of Figure 4.

Figure 6 is a horizontal section taken on the line 6—6 of Figure 4.

Figure 7 is a detail horizontal sectional view through the casing.

Referring to the drawings in detail, wherein similar reference characters designate corresponding parts throughout the several views, the letter 'B' generally indicates my improved metallic barrel, which comprises an outer protecting casing C and an inner liner L.

The liner L is preferably formed from sheet metal, and the same includes a side wall 10 and end walls, or heads, 11 and 12. The liner is preferably formed from a single piece of material, but if desired, the same can be made in upper and lower sections suitably welded together, as at 13.

The side wall 10 can either be of the straight or bilged type, and one head 11 carries a neck 14.

A similar neck 15 is carried by the side wall 10. These necks 14 and 15 can be welded in place and form a part of my novel bung and tap hole construction.

The liner can be cast at a foundry in one piece with bung and tap cast thereon.

It is preferred to make the liner L of noncorrosive material, such as aluminum or copper, so that the necessity of pitching the barrel for beer will be eliminated. However, it is to be understood that my barrel is susceptible for use

in shipping liquids other than beer and is particularly useful in shipping acids, in which instance the liner can be made from glass or porcelain.

5 The outer casing C is also preferably formed from sheet metal, and the same includes a top section 16 and a bottom section 17. These sections are united tightly together by a novel means, which will be later described. The sections are shaped to conform to the configuration of the liner but of a greater size, so that the liner will be spaced therefrom.

10 The top section 16 includes a circular side wall 18 and an end wall, or head, 19. At the point 15 of juncture of the head 19 with the side wall 18, the section is rolled to provide an annular protecting bead 20.

15 The bottom section 17 is formed similar to the top section 16, and also includes a circular side 20 wall 21 and an end wall, or head, 22. An annular bead 23 is formed around the head 22 to protect the same.

20 By referring to Figure 1 of the drawings, it will be noted that the inner edge of the side wall 25 16 is tapered, as at 24, so as to fit snugly within the side wall 21 and to make a tight contact therewith. As shown in Figure 7, the sections can be provided at spaced points with short longitudinally extending mating ribs and grooves 46, so 30 as to prevent twisting or turning of the sections. The side wall, above the tapered inner end 24, is provided with a fast screw thread 25, which can be struck out from the side wall.

25 A locking ring 26 is provided for connecting the sections together, and this locking ring includes an inner metallic band 27, one end of which has struck out therefrom a screw thread 28 for the receipt of the screw thread 25 on the section 16. The other end of the band is tapered, as at 29, 40 so as to snugly engage the side wall of the section 17.

30 A protecting band 30 is placed around the inner band 27, and the meeting edges of the bands 27 and 30 can be suitably welded together. The 45 outer band 30 gives the desired rigidity to the inner band and protects the screw threads against injury.

35 When the casing sections 16 and 17 are being united, the locking ring 26 is slipped over the 50 outer end of the section 17 and is then threaded on the section 16. The tapered faces of the side wall 21 and the band 29 tend to draw the sections tightly together, as is readily apparent. Thus, in effect, a seal is formed at the meeting 55 edges of the sections and the screw threads 25 and 28, and at the meeting faces of the band 29 and the side wall 21.

40 If desired, the ring 26 and the section 16 can be grooved for the reception of a wedge 47, which 60 functions to hold the ring against accidental turning movement after adjustment. However, sleeve 45 (hereinafter specifically referred to) will serve this purpose admirably.

45 In order to hold the liner L in proper spaced 65 relation to the casing C, longitudinally extending non-heat conducting strips 31 are provided. These strips are preferably formed from wood, as not only is wood a non-heat conductor, but the same will also act as a cushion to prevent 70 the transmission of shock to the liner. These strips 31 are arranged at spaced points around the liner, and the casing is provided with lugs 32 which are received in cavities 33 formed in the strips, so that displacement of the strips will 75 be prevented. Top and bottom wooden spacing

rings 34 and 35 are also provided, and these spacing rings fit between the ends of the casing and the ends of the liner. Lugs 36 can be carried by the end wall 22 of the casing for engaging in cavities formed in the wooden ring 35, so as to prevent movement thereof.

10 The strips 31 are preferably formed in upper and lower sections to facilitate the assembling of the barrel, and these strips, as well as the ring 35, are provided with openings 48, whereby to permit the free circulation of air around the liner. This permits an even temperature all around the liner.

15 In order to form the end bung, or tap hole, the end wall, or head, 19 of the casing is struck inwardly, as at 37, to provide the right angularly disposed flanges 38 and 39. The wooden spacing ring 34 engages about the flange 38 and forms a means for protecting this flange against being crushed incident to the rough handling of the 20 barrel, and this flange also prevents lateral shifting of the ring.

25 A suitable gasket 40 is placed between the neck 14 and the flange 39, and a shouldered collar 41 is threaded into the neck and against the flange 39. The collar 41 can be suitably formed so as to receive the desired tap fittings.

30 The side bung for the barrel is formed similar to the bung, or tap hole, just described, and the casing has its sections 17 provided with an enlarged opening which is adapted to register with the side neck 15, and a gasket 42 is interposed between the neck and the casing wall.

35 The locking ring 26 is also provided with an opening 43 which is adapted to align with the opening in the casing wall when the ring has been threaded tightly in place. The locking ring is preferably shouldered, as at 44, around the opening formed therein, and a shouldered locking sleeve 45 is threaded into the sleeve 15 and against the shoulder 44. This sleeve 45 40 can also be formed to receive the desired type of tap fittings.

45 From the foregoing, it can be seen that I have provided an exceptionally simple and durable type of metallic barrel, which is particularly susceptible for the shipping and storing of beer. The casing C will effectively protect the inner liner L from blows, and thus the inner liner can be formed from relatively thin material. Likewise, the spacing of the casing from the liner prevents 50 the transmission of heat from the casing to the liner, and the only points of metallic contact between the liner and the casing is at the bung and tap holes.

55 While the barrel illustrated in Figures 1, 2 and 3 is the preferred form, the barrel is open to modification, and in Figures 4, 5 and 6 I have illustrated another form thereof.

60 In this form the outer casing is cast, although the same can be made from sheet metal. The casing is divided longitudinally to form the companion sections 50 and 51. Each section forms one half of the casing and includes a semi-cylindrical, bilged side wall 52 and an integral 65 head 53. The heads are arranged at the opposite ends of the casing, and the inner surfaces of the sections are grooved, as at 54, to receive the edges of the heads when the sections are united.

70 I preferably employ two locking rings 55 for uniting the sections together, and these rings are arranged on opposite sides of the transverse center of the casing, and the casing is provided with external threads 56 on which the rings are threaded. The inner faces of the rings beyond 75

the threads are also tapered, as at 51, so as to tightly draw the sections together.

After the rings are threaded tightly in place, the same can be held against movement by wedges 58 which can be driven in mating recesses formed in the rings and the outer faces of the casing sections. The grooves for the wedges are so arranged on the rings and sections that different adjustments of the rings can be had.

10 The barrel in all other respects is formed identical with that form of my barrel shown in Figures 1 to 3 inclusive.

Changes in details may be made without departing from the spirit or the scope of my invention, but what I claim as new is:—

15 1. A barrel comprising, a liner for the reception of liquids, and a removable sectional protecting casing formed of sheet metal, each of said sections including an annular side wall and a head, 20 the meeting ends of the sections being fitted one within the other, and one of said sections having struck out therefrom a fast thread, a ring for uniting said sections together, including inner and outer metallic bands, the inner band having 25 a thread struck out therefrom for engaging the thread on the last mentioned section, and

a tapered inner face for engaging the other section and barrel tapping means carried by the liner and extending through the casing, whereby the contents of the liner can be dispensed without disturbing the casing.

2. A barrel comprising an inner liner for the reception of liquids having an outwardly projecting neck, an outer protecting casing including a pair of removable sections, each of said sections including an annular side wall and an integral head, the meeting ends of one of the sections being fitted one within the other, one of said sections being provided with a screw thread, a uniting ring threaded on the last mentioned section and having a tapered inner face for engaging the other section for drawing the meeting ends of the sections into intimate contact when the ring is turned tightly in said threads, said ring having an opening adapted to register with the neck, and an external threaded sleeve 20 movable through said opening into threaded engagement with the neck having a shoulder for engaging the ring to prevent accidental turning movement thereof.

SIMON DEUTSCH. 25
